CONTROL SHAFT

Harry W. Rubinstein, Milwaukee, Wis., assignor
to Globe-Union Inc., Milwaukee, Wis., a corpora-
tion of Delaware

Application June 14, 1940, Serial No. 340,426

1 Claim. (Cl. 287—53)

This invention relates to an improvement in control shafts especially designed and adapted for use with electrical control devices of the type employed on radio sets, such, for example, as volume controls, tone controls, variable condensers, adjustable rheostats, switches, and the like.

A control shaft of this character is usually actuated or adjusted by means of a manually rotatable control knob mounted on and rotatively coupled to the outer end of the shaft. To adapt the shaft for this interconnection and rotative coupling with the control knob, it has been the practice in the art to flatten the outer end portion of the shaft. Because different styles of knobs require different degrees of flattening, it has been difficult to standardize the manufacture of control shafts and avoid laborious and expensive modification thereof when assembling. This has led to the expedient of combining removable inserts with a specially constructed ridged shaft, as proposed in Patent No. 2,197,140, granted April 16, 1940, to M. J. Arvin, for a "Control shaft."

The object of the present invention is to provide a control shaft which avoids the use of any inserts or extra parts. When constructed in accordance with the present invention, the control shaft is an integral article of manufacture and yet may be conveniently and effectively utilized with the various types of knobs.

In carrying out the present invention at least the end portion of the shaft is flattened and is characterized by the provision of a plurality of ribs separated by a plurality of narrow grooves. The ribs have flat top surfaces located in the same plane to present a flat on the shaft of substantial area to adapt it to be effectively interfitting with a large sized socket of a control knob. The grooves between the ribs are of uniform, predetermined depth and have flat floors lying in the same plane. As the ribs are constituted of material readily filed away, or readily removable in any other appropriate fashion, the shaft may be easily converted for use with a small sized socket of a control knob merely by filing the ribs down to the level of the floors of the grooves.

Other objects and advantages reside in certain novel features of the construction, arrangement, and combination of parts, which will be hereinafter more fully described and particularly pointed out in the appended claims, reference being had to the accompanying drawing forming a part of this specification, and in which:

Figure 1 is a view in side elevation showing an

electrical control device equipped with a control shaft embodying the present invention.

Figure 2 is a view in transverse cross section taken on line 2—2 of Figure 1 and showing the ribs still in place on the shaft.

Figure 3 is a view similar to Figure 2 but illustrating the construction of the shaft after the ribs have been removed or filed away.

Figure 4 is a fragmentary view partly in side 10 elevation and partly in longitudinal, vertical cross section, showing how a control knob is combined with the outer end of the shaft with the ribs thereon.

Figure 5 is a view similar to Figure 4 but illustrating the control knob combined with the shaft 15 after the ribs have been filed away.

Referring to the drawing, the numeral 10 designates an electrical control device, such as a volume control, or any other similar type of 20 control. The device is regulated in its action by means of a control shaft 11 which is supported for rotation in the bushing 12 of the volume control in the usual way.

Beyond the bushing 12 the shaft is flattened, 25 and the flattened portion is formed with a plurality of parallel, longitudinally extending ribs 13 separated by grooves 14. In the preferred embodiment of the invention at least three such ribs are provided. The ribs have flat top surfaces which lie in the same plane so that the top surfaces present a flat of substantial area 30 adapted to be effectively interfitted with the socket of a control knob 15, in the manner illustrated in Figure 4. The grooves 14 are of uniform, predetermined depth and have flat floors 15 lying in the same plane. The shaft is usually 35 constructed of suitably soft metal, such as aluminum alloy, or the like, so that the ribs 13 may be readily filed or cut away down to the 40 level of the floors 15 of the grooves 14. This produces a shaft with a flat adapted to be combined with a knob 17 having a small sized socket 45 therein in the manner illustrated in Figure 5.

In Figures 4 and 5 the outer ends of the shaft 50 11 are merely shown as frictionally interfitted with the sockets of their control knobs. Of course, various well-known types of fastening devices may also be employed to effect the desired interconnection between the sockets of the knobs and the outer ends of the shaft. Then, again, in Figures 2 and 3 it is indicated how the 55 dimensions of the shaft are varied by filing away the ribs. Of course, the present invention is not limited to any particular dimensions.

While I have shown and described one con-

struction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claim.

I claim:

A control shaft for use with control knobs having shaft receiving sockets of different dimensions, said shaft having an end portion thereof provided with a flat face disposed in a plane substantially parallel to the axis of said shaft, the flat face of said shaft being provided with a

5 plurality of slots extending longitudinally of the shaft and penetrating said flat face to a substantially uniform depth, the several slots each terminating in a flat floor, the several slot floors being separated by upstanding ribs, all of said floors being disposed in a common plane substantially parallel to the plane of said flat face, the said flat face being dimensioned to properly fit within the shaft receiving socket of a knob having a large socket and the flat face collectively defined by the floors of said slots when the ribs are removed being dimensioned to properly fit within the shaft receiving socket of a knob having a small socket.

HARRY W. RUBINSTEIN.
